CARD INDEX

Julian C. Williams, Ozone Park, N. Y., assignor
to Art Metal Construction Company, James-
town, N. Y., a corporation of Massachusetts

Application December 10, 1937, Serial No. 179,141

5 Claims. (Cl. 129—16.7)

This invention relates to paper files and is more particularly concerned with card indexes and filing elements. It is especially useful in connection with card indexes of the so-called "visible" type, in which the filing elements are overlapped and have exposed margins to receive identifications. In many such files, the index elements are carried by carriers whose ends are received in channels of a panel, and the present invention deals with filing elements intended to be used in such an arrangement.

The invention will best be understood by reference to the following description when taken in connection with the accompanying drawings of one specific embodiment thereof, while its scope will be pointed out more particularly in the appended claims.

In the drawings:

Fig. 1 is a front elevation of a card carrier, a card holder, and cards held by the latter, embodying the invention;

Fig. 2 is a rear elevation of the same;

Fig. 3 is an elevation of a sheet which, when folded, constitutes the principal part of the card holder;

Fig. 4 is a sectional view, on an enlarged scale, on line 4—4 of Fig. 1; and

Fig. 5 is a sectional view, on an enlarged scale, on line 5—5 of Fig. 1.

Referring to the drawings and to the embodiment of the invention illustrated therein by way of example, there is shown in Fig. 3 a sheet 1 of appropriate material, such as paper, provided with two tabs 9 initially projecting from opposite edges 11 of the sheet and herein conveniently formed as integral parts of the sheet. As herein shown, each tab is in the form of an isosceles triangle, for example a right angle triangle whose hypotenuse is coincident with the edge 11, and the tab is foldable along the hypotenuse represented by the broken line X—X. The sheet is also foldable along a line Y—Y perpendicular to the two lines X—X and bisecting the right angles of the triangles.

By folding the sheet first along the lines X—X the tabs are folded inwardly toward each other, and then by folding the sheet along the line Y—Y, there is formed a flap 13, and there are also formed a pair of corner pockets 15—15 overlying the front face of the card holder, and a pair of corner pockets 17—17 overlying the rear face of the card holder, or perhaps more properly the rear, outer face of the flap 13. The corner pockets 15—15 receive two corners of a card 19 applied to the front face of the card holder, and the

corner pockets 17—17 receive two corners of a card 21 applied to the rear face of the card holder.

The remaining corners and in fact the entire lower margins of the cards 19 and 21 are received in a sheath 23 of appropriate sheet material such as Celluloid folded (see Fig. 4) to present a front wall 25 and a rear wall 27. The space between these walls receives the lower margins of the cards 19 and 21 as well as the intermediate margin of the card holder 1. In the example shown, the sheath is interlocked with the sheet holder by providing the front wall of the sheath with a downwardly directed lip 29 and by providing the card holder with a flap 31 (see Fig. 3) foldable along a line z—z and directed upwardly (see Fig. 4) between the lip 29 and the front wall 25. The sheath is, of course, applied by sliding the same lengthwise.

The flap 31 may serve to receive identifying matter which will be exposed to view at all times. In the example shown, the flap 31 does not extend the full length of the margin of the card carrier, and thus there is left a space (see Fig. 1) to receive signal elements or other appropriate indexing. To prevent the sheath from moving lengthwise, fastening means such as a rivet 33 (see Fig. 5) passes through the front and rear walls 25 and 27 of the sheath and through the intermediate margin of the sheet holder 1. As herein shown, the front card 19 is provided with a notch 35 (see Fig. 1) and the rear card is provided with a notch 37 (see Fig. 2) to receive the rivet.

The sheet holder may be hung upon an appropriate hanger such as a wire 39 having terminal enlargements in the form of trunnions 41 intended to be received in the channels of a panel and to provide the necessary overlap or exposure of the identification receiving margin of the sheet holder. The sheet holder is conveniently supported on the hanger as by passing the latter through perforations in the former. In the example shown, the sheet holder is provided with perforation 43—43 between its edges 11 and intersected (herein bisected) by the fold line Y—Y, and it is further provided with perforations 45—45 in the tabs 9 and also similarly intersected by the fold. The two sets or pairs of perforations are so located that when the tabs are folded inwardly the perforations of one pair coincide with the perforations of the other pair (see Figs. 1 and 2). To insert the carrier, the flap 13 is folded upwardly, the wire is introduced through the coincident perforations at one end, and is then passed through the coincident perforations 45—45.

rations at the other end. The flap is then folded down to embrace the wire, and according to the preferred arrangement the principal portion of the wire is within the principal portion of the fold, so that only two small portions of the wire (see Fig. 1) appear overlying the corner pockets 15-15.

The cards may be employed to receive any desired records, and either or both sides of the 10 cards may be used. Records might be written on the card holder, but ordinarily the cards will suffice.

Having thus described one embodiment of the invention, what I claim and desire, by Letters 15 Patent, to secure is:

1. A card holder comprising a sheet folded to present a flap overlying one face thereof, and two tabs initially projecting from opposite ends of the flap and from opposite edges of the sheet and 20 folded to present two pairs of corner pockets, one pair on one face of the sheet.

2. A card holder comprising a sheet having two tabs initially projecting from opposite edges of the body of the sheet, said tabs and the body of 25 the sheet being provided with perforations and being folded along a line intersecting said perforations, and forming a flap overlying one face of the body of the sheet, and said tabs being folded inwardly toward each other along lines substantially 30 coincident with opposite edges of said body to present two pairs of corner pockets, one pair overlying said flap and the other pair overlying the opposite face of said body, the perforations in said tabs substantially registering with the remaining 35 perforations.

3. A card holder comprising a sheet having two

tabs initially projecting from opposite edges of the body of the sheet, said sheet being folded along a line which extends across the body of the sheet and across said tabs and forming a flap overlying one face of the body of the sheet, said 5 tabs being folded inwardly toward each other along lines substantially coincident with opposite edges of said body to present two pairs of corner pockets, one pair overlying said flap and the other overlying the opposite face of said body. 10

4. A card holder comprising a sheet having two tabs, each in the form of a triangle, initially projecting from opposite edges of the sheet, and with an apex directed outwardly, the sheet being folded along a line connecting said apexes and 15 parallel with a third edge of the sheet, and forming a flap overlying one face of the sheet, said tabs being folded inwardly toward each other and forming four pockets arranged in pairs, one pair overlying the outer face of said flap; and the 20 other pair overlying the second face of the sheet.

5. A card holder comprising a sheet having two tabs initially projecting from opposite edges of the sheet, each tab being in the form of an isosceles right angle triangle whose hypotenuse is 25 coincident with one of said edges, and whose right angle is direct outwardly, the sheet being folded along a line bisecting the right angles and parallel with a third edge of the sheet and forming a flap overlying one face of the sheet, said 30 tabs being folded inwardly toward each other, each along its hypotenuse, and forming four pockets arranged in pairs, one pair overlying the outer face of said flap, and the other pair overlying the second face of the sheet.

JULIAN C. WILLIAMS.
